US0D1077478S

(12) United States Design Patent (10) Patent No.: US D1,077,478 S
(45) Date of Patent:  Jun. 3, 2025

(54) SHOE BOX

(71) Applicant: DELI GROUP CO. LTD, Ningbo (CN)

(72) Inventors: Hongyu Qi, Zhejiang (CN); Yuangang Yang, Zhejiang (CN)

() Term: 15 Years

(21) Appl. No.: 35/521,472

(22) Filed: Apr. 29, 2024

(80) Hague Agreement Data

Int. Filing Date: Apr. 29, 2024

Int. Reg. No.: DM/237891

Int. Reg. Date: Apr. 29, 2024

Int. Reg. Pub. Date: Jun. 28, 2024

(30) Foreign Application Priority Data

Oct. 31, 2023 (CN) 202330708308.1

(51) LOC (15) Cl. 03-01

(52) U.S. Cl.

USPC D3/321; D3/273

(58) Field of Classification Search
